UNITED STATES PATENT OFFICE.

SAMUEL S. WILLIAMSON, OF PHILADELPHIA, PENNSYLVANIA.

NON-REFILLING BOTTLE.

1,102,560.

Specification of Letters Patent. Patented July 7, 1914.

Application filed March 25, 1910. Serial No. 551,536.

To all whom it may concern:

Be it known that I, SAMUEL S. WILLIAMSON, a citizen of the United States, residing at Philadelphia, in the county of Philadelphia and State of Pennsylvania, have invented a new and useful Improvement in Non-Refilling Bottles, of which the following is a specification.

My invention relates to a new and useful improvement in non refillable bottles and has for its object to provide a simple and cheap construction which while permitting the liquid to flow out of the bottle will prevent any liquid from being forced into it.

In the accompanying drawings: Figure 1, is a section of a portion of bottle showing my improvement applied thereto. Fig. 2, is a similar view showing the bottle inverted. Fig. 3, is a section at the line 3—3 of Fig. 1. Fig. 4, is a detail section of the valve case and seat; and Fig. 5, is a plan view of the valve.

In carrying out my invention as here embodied (A) represents a bottle having a short neck threaded at (B) and this neck has a beveled edge (C).

(D) is an attachable neck having screw threads in its lower end for engagement with the threads (B), and also having a groove 30 (E) formed just above the threads for the reception of a suitable cement. This groove has depressions or corrugations (F) formed therein and corresponding depressions (G) are formed upon the short neck so that when 35 the attachable neck is screwed into place the cement in the groove (E) will be forced into these depressions and when set this cement will lock the neck (D) against removal, as will be readily understood.

(H) represents the valve case which is cylindrical, open at the top and has the valve seat (I) formed in its bottom. This valve case fits loosely in the neck (D).

(J) represents the keeper which rests on 45 the top of the valve case and is held in place by the shoulder (K) formed on the inside of the neck (D); this keeper may be of any suitable design to prevent tampering with the mechanism contained in the valve case, and in its under side is formed a conical recess (L) for the purpose which will herein-after appear.

(M) represents the valve, the lower end of 55 which is conical to fit the conical seat (I) and both the seat and that portion of the valve which fits therein should be ground to insure

a perfect fit. Formed with the body of the valve are lugs (N) adapted to guide the valve in the case so as to cause it to move off or on its seat in an axial line only, which is of great importance in the successful operation of the device as hereafter shown. The top of the body of the valve is conical as indicated at (O) the angle thereof being less or nearer the horizontal than the angle of the conical recess (L) and on the conical top (O) is placed a ball (P). As this ball is confined between the conical top (O) and the walls of the conical recess (L) it will rest in the wedge shaped space formed by the angles of the walls of the two cones and hold the valve upon its seat. The body of the valve is hollow or of material which will float, so that should the bottle be inverted as shown in Fig. 2 any attempt to immerse it or force liquid upward therein will close the valve seat. The bottle may be tipped considerably without the ball releasing the valve, but should it be tipped beyond a predetermined point, the ball will roll down the incline of the conical recess (L) permitting the valve to slide open and the contents of the bottle to flow out.

In returning the bottle to its normal position the ball will close the valve before the bottle reaches a horizontal position thus cutting off the flow of the liquid from the bottle but permitting any liquid in the neck to escape.

Many devices have been made which would prevent a bottle from being refilled by forcing liquid into the neck or by drawing a vacuum in the bottle, but little or no provision has been made for holding the valve on its seat when the bottle is subjected to vertical vibrations or a sudden jar on the bottom, and such treatment will cause the ordinary valve to jump from its seat and permit the liquid to flow in. My device is therefore especially designed to prevent the refilling of a bottle by these methods, which is accomplished by the ball being confined between the surfaces (L) and (O) which are at such an angle to each other that vertical vibration will tend to jam the ball into the wedge shaped space formed by these two surfaces, and from the further fact that the valve is so guided that it must slide straight on an axial line, while such a movement would crowd the ball sidewise and therefore only bind it more tightly. A cork or other suitable gasket (Q) is interposed between

the inclined edge (C) and the bottom of the valve case (H) to pack the parts at this point. All the parts except this gasket may be made of glass.

5 To make the bottle doubly secure against refilling I use a locking pin (a) fitted to slide freely in a hole (b) in the keeper, and this pin rests against the ball (P) when the bottle is in an upright position and remains 10 in contact therewith till the bottle is tipped beyond the horizontal when it will slide into the hole and free the ball. This construction has many advantages, one of which is that the ball is positively locked against being jarred out of contact with the valve, and another advantage is the pin assists in crowding the ball into the wedge shaped space, thus more firmly pressing the valve 15 on its seat.

20 Having thus described my invention what I claim is—

1. In a non-refilling device consisting of a buoyant valve, a valve seat to which said valve is fitted, a ball normally resting upon 25 said valve, and a plunger fitted to slide in a straight line adapted to automatically lock the ball upon the valve.

2. In a device of the character described, a valve casing, a valve seat formed therein, 30 a buoyant valve fitted to slide in said casing, a ball normally resting on the top of the valve, and a keeper fitted over the ball and a plunger fitted to slide in the keeper on the axial line of the valve and automatically 35 lock and unlock the ball by the change of position of the device.

3. In a non-refillable receptacle, the combination of a valve seat therein, a valve 40 adapted to co-act with said seat, a keeper mounted above the valve and having a straight bore in its vertical center open at its inner end, a plunger snugly fitted in said bore so as to move only on said vertical center, and a ball disposed between the keeper 45 and valve, and adapted to coöperate with the valve and plunger.

4. A non refilling bottle comprising a body, a neck, a valve case secured in said neck, a buoyant valve adapted to close upon 50 a valve seat formed in the case, a keeper also secured in the neck and having a conical shaped recess formed in its under side, a ball adapted to wedge in the space formed between the valve and keeper and a sliding 55 pin moving in a straight axial line with the valve adapted to automatically lock the ball in contact with the valve when the bottle is in certain positions and release said ball when the bottle is in certain other positions.

60 5. In a bottle, a non refilling device consisting of a valve seat, a valve, a ball adapted to contact with said valve and a vertical

sliding plunger adapted to automatically lock said ball in contact with the valve, when the device is in certain positions and release said ball when the device is in certain other positions.

6. In a non-refillable bottle, the combination of a bottle neck, a valve seat therein, a valve for coöoperating with the seat, a body 70 fixed in the neck and having a bore in its vertical center, which bore is straight and open at its lower end, a plunger permanently fitting in a snug manner and movable rectilinearly up and down in the said bore 75 of the body and held against movement in other directions, and movable means disposed in the bottle neck and between the valve and the plunger and adapted to operate therewith, substantially as specified. 80

7. The combination with a bottle neck, of an upwardly opening valve therein, a retainer normally resting on said valve to hold it in closed position, and means axially maintained throughout for normally locking said retainer laterally against diametric movement on said valve, but permitting movement of said retainer to releasing position when the bottle is inverted.

8. The combination with a bottle neck, 90 of an upwardly opening valve therein, a retainer normally resting on said valve to hold it in closed position, and means axially maintained throughout for normally locking said retainer by lateral engagement 95 against any but a movement in the path of a circle on said valve, but permitting movement away from said valve when the bottle is inverted.

9. The combination with a bottle neck, 100 of an upwardly opening valve therein, a ball normally resting on said valve to hold it in closed position and disposed in a chamber above said valve having a cone-shaped upper face, and means for normally retaining 105 said ball away from the center of said chamber and against said cone-shaped upper face, but permitting movement toward the center when the bottle is inverted.

10. The combination with a bottle neck, 110 of an upwardly opening valve therein, a ball normally resting on said valve to hold it in closed position and disposed in a chamber above said valve having a cone-shaped upper face, and a vertically shiftable rod 115 engaging the side of said ball for normally retaining said ball away from the center of said chamber, but permitting movement toward the center when the bottle is inverted.

SAMUEL S. WILLIAMSON.
